APPARATUS FOR PREVENTING THE ACCUMULATION OF ICE

Millard R. Bell, Cuyahoga Falls, and Charles S. Stebbins, Akron, Ohio, assignors to The B. F. Goodrich Company, New York, N. Y., a corporation of New York

Application August 3, 1940, Serial No. 350,488

6 Claims. (Cl. 244—134)

This invention relates to apparatus for preventing the accumulation of ice and more particularly to inflatable and stretchable shoes adapted to be mounted upon the leading edges of wings or other air foils or parts of aircraft.

The invention relates more especially to improvements in such shoe construction, providing for a smooth and even surface contour, uniform thickness thereof, and at the same time making possible effective stretching of areas thereof to break up and loosen ice accumulations for removal by air flow.

These and further objects will be apparent from the following description, reference being had to the accompanying drawing in which:

Fig. 1 is a plan view of a wing tip having an ice-removing shoe mounted upon its leading edge, which shoe is constructed in accordance with and embodies the invention.

Fig. 2 is a section taken along the line 2—2 of Fig. 1.

Fig. 3 is a perspective view of a portion of the structure of Fig. 2, the parts being shown in stepped relation for clarity of illustration.

Fig. 4 is a view like Fig. 3, but showing a modified construction.

Fig. 5 is a view like Fig. 3, but showing a still further modified construction.

To the end of providing for a stretchable area of the shoe between its margin of attachment and the region of its inflatable elements, there is provided means, preferably in the form of a sponge rubber body or bodies, in such stretchable area and so associated with the shoe that stretching is effected without altering the surface shape of the shoe or the thickness thereof, so that the surface remains in its most effective condition aerodynamically, whether the shoe is in a condition of rest or is distended in operation.

The sponge rubber body, by virtue of the resilience thereof, has a further advantage in being effective to cushion the shocks of impact from hail, stones or other material striking the surface. In some cases it will be desirable to extend the sponge rubber body to occupy a large part of the area of the covering.

The invention, according to the embodiment of Figs. 1, 2 and 3 is illustrated as applied to an inflatable shoe 10 mounted upon the leading edge of the wing 11 of an aircraft. The shoe 10 comprises an elastic body of rubber or rubber-like material comprising an outer elastic sheet 12, and an inner elastic sheet 13, between which sheets in the central region thereof are disposed inflatable tubes 14 and 15, preferably united inte-

grally with the sheets 12 and 13 by vulcanization. The upper and lower margins of the sheets are preferably reinforced by means of strip fabric 16 to which the cover sheets 12 and 13 are secured and these margins are secured to the wing skin as by means of screws 17, 17 extending through apertures in the margins into hollow rivets 18, 18 mounted in the skin.

Upon distension of the shoe in its inflated condition the area between the tubes 14, 15 and the attaching margins is subjected to considerable stretch upon being pulled away from the wing. It is desirable, of course, not to hinder such stretchability. At the same time it is desirable to maintain a uniform thickness of the shoe throughout its extent including such stretch area so that it will maintain an even surface. These purposes are accomplished in accordance with the present invention by provision in such stretch area of a body 19 of bulky but light, resilient material, preferably sponge rubber. The body 19 of sponge rubber may be built into the shoe in the manner of Fig. 3 by assembling it between the cover sheets 12, 13, preferably with layers of cement 20, 21 adhering the body 19 to such cover layers. Provision is made for tying the sponge rubber body at its margins to the adjacent parts of the shoe, a fillet 22 of rubber being provided at one margin for uniting the sponge rubber body 19 with the tube 14 and providing a smooth surface of the cover 12 overlying this junction. At the other margin of the sponge rubber body 19 there may be provided a strip 23 of rubber preferably inset in the sponge rubber body 19 as shown and positioned in adhesive contact with the end surface of the rubberized fabric strip 16 to resist separation at this juncture and provide a smooth and flush surface of the cover 12 thereover. For additionally strengthening the juncture of the body 19 with the rubberized fabric 16, a strip 24 of rubberized fabric may be provided at the end surface of the body 19 between the latter and the under sheet 13 and overlying such juncture.

All the parts of the shoe 12 preferably are united integrally by vulcanization. The cover sheet 12 preferably terminates short of the ultimate margin as shown to provide space for fairing strips 25, 25 in flush relation, which fairing strips are held in place by the marginal securing screws 17, 17.

A shoe constructed in accordance with the foregoing has the advantage of maintaining a constant thickness throughout its extent upon the leading edge of the wing and provides the desired aerodynamic surface. Also, when the

sheet is distended upon inflation of its tubes to a position such as that indicated by the broken lines 26 (Fig. 2) the stretchable area referred to is not hindered from performing its stretching function and the surface throughout this area is distended in a smooth and regular manner so that aerodynamic drag is minimized.

In the embodiment of Fig. 4 a sponge rubber body 30 is secured to a wing surface 31 as by means of a layer of adhesive 32, this sponge rubber body 30 being located within the stretch area of a shoe 33 comprising upper and lower elastic cover sheets 34 and 35 respectively, inflatable tubes 36, 37, and a reinforced attaching margin 38. The shoe may be set within a recess in the leading edge of the wing which recess terminates in a shoulder 39. The reinforced margin 38 is attached to the wing skin by means of screws 40 extending through the margin and such screws may be used also to hold a fairing strip 41 in place in a manner to provide a flush surface at the shoulder 39.

In the embodiment of Fig. 4 the body 30 of sponge rubber is not attached directly to the shoe 33, but is adhered only to the underlying wing surface, the elastic shoe upon forward distension being adapted to slide over the sponge rubber body 30 and even to extend away from contact with the same during such distension. The body of sponge rubber 30, however, serves to fill out the space in such stretch area to provide a uniform thickness of the shoe when mounted in place and a smooth aerodynamic outer surface of such shoe.

In the embodiment of Fig. 5 the construction differs from that of Fig. 4 in that a sponge rubber body 50 is secured, not to the wing skin, but to the distensible shoe 51 at the under surface thereof in its stretched region. The shoe may comprise upper and lower elastic sheets 52, 53, an intermediate inflatable element 54 and a reinforced margin 55 which may be attached to the wing skin by means of screws 56 in the manner hereinbefore explained, which screws may serve also to hold a fairing strip 57 in place.

The body 50 of sponge rubber is adhered to the under surface of the lower elastic sheet 53 and provides the uniform thickness of the shoe by filling out the stretch area thereof. Upon distension of the shoe when inflated, the sponge rubber body 50, being stretchable and resilient, is capable of stretching along with the cover sheets in the stretch area so as not to hamper the distending function of the shoe and when the shoe recovers from its distension the sponge rubber body returns to the normal, unstretched shape shown.

Variations may be made without departing from the scope of the invention as it is hereinafter claimed.

We claim:

1. Means for preventing the accumulation of ice comprising inner and outer extensible sheets, means for attaching the same to a surface along 5 a zone thereof, an inflatable element incorporated with said sheets in a portion spaced from the attaching zone by a stretchable area of said sheets, and a body of sponge rubber incorporated with the elastic sheets in said stretchable area in 10 a manner providing a substantially uniform thickness of the structure such as to provide a flush and even outer surface thereof.
2. Means for preventing the accumulation of ice as defined in claim 1, in which the said body of 15 sponge rubber is disposed between said elastic sheets and secured thereto in the said extensible area thereof.
3. Means for preventing the accumulation of ice as defined in claim 1 in which the body of sponge 20 rubber is mounted between the under elastic sheet and the surface of the aircraft.
4. A protective covering for aircraft comprising an extensible surface layer having an attaching portion, an inflatable portion spaced therefrom and 25 an intervening stretchable portion, and a filler element of resilient sponge rubber material substantially coextensive with said stretchable portion and disposed beneath the surface thereof providing a normal thickness of said 30 stretchable portion such that its outer surface is substantially flush and even with the adjoining surface of said inflatable portion when the covering is mounted upon the aircraft.
5. A protective covering for aircraft comprising 35 an extensible layer having an attaching portion, an inflatable portion spaced therefrom and an intervening stretchable portion, and a filler element of resilient sponge rubber material united with adjacent material of the covering and disposed beneath the surface of said stretchable portion providing a normal thickness of said 40 stretchable portion such that its outer surface is substantially flush and even with the adjoining surface of said inflatable portion when the covering is mounted upon the aircraft.
6. A protective covering for aircraft comprising 45 an extensible surface layer having an attaching portion, an inflatable portion spaced therefrom and an intervening stretchable portion, and a filler element of resilient sponge rubber material united with said layer at said stretchable portion beneath the surface thereof providing a normal thickness of said stretchable portion such that its outer surface is substantially flush and even with the adjoining surface of said inflatable portion when the covering is mounted upon the aircraft.
